[57] CLAIM

The ornamental design for a two-ended tool handle, as shown and described.

DESCRIPTION

FIG. 1 is a front perspective view of a two-ended tool handle showing my new design;

FIG. 2 is a left side elevation view of the two-ended tool handle of FIG. 1;

FIG. 3 is a right side elevation view of the two-ended tool handle of FIG. 1;

FIG. 4 is a top plan view of the two-ended tool handle of FIG. 1;

FIG. 5 is a bottom plan view of the two-ended tool handle of FIG. 1;

FIG. 6 is a front end view of the two-ended tool handle of FIG. 1;

FIG. 7 is a rear end view of the two-ended tool handle of FIG. 1;

FIG. 8 is a front perspective view of an alternate embodiment of the two-ended tool handle of FIG. 1;

FIG. 9 is a left side elevation view of the two-ended tool handle of FIG. 8;

FIG. 10 is a right side elevation view of the two-ended tool handle of FIG. 8;

FIG. 11 is a top plan view of the two-ended tool handle of FIG. 8;

FIG. 12 is a bottom plan view of the two-ended tool handle of FIG. 8;

FIG. 13 is a front end view of the two-ended tool handle of FIG. 8; and,

FIG. 14 is a rear end view of the two-ended tool handle of FIG. 8.

The broken line portions of the disclosure are for illustrative purposes only and form no part of the claimed design.
